UNITED STATES PATENT OFFICE.

GEORGE F. MCKEEVER, OF ALLEGHENY, PENNSYLVANIA, ASSIGNOR OF TWO-THIRDS TO FREDERICK BARKER AND JAMES MCKEEVER, JR., OF PITTSBURG, PENNSYLVANIA.

PACKING BARREL, KEG, OR TIERCE.

SPECIFICATION forming part of Letters Patent No. 655,103, dated July 31, 1900.

Application filed March 9, 1900. Serial No. 7,953. (No model.)

To all whom it may concern:

Be it known that I, GEORGE F. MCKEEVER, a resident of Allegheny, in the county of Allegheny and State of Pennsylvania, have 5 invented a new and useful Improvement in Packing Barrels, Kegs, or Tierces; and I do hereby declare the following to be a full, clear, and exact description thereof.

My invention relates to a combined head, 10 groove, and hoop for ordinary wooden barrels, kegs, tubs, and similar devices, its object being to provide a device of this character which is easy and cheap to manufacture, which may be readily applied to the barrel 15 and form a strong closure therefor, and which may be used in assembling the staves. The ordinary wooden barrel as now constructed is made up of a series of staves having grooves on their inner surfaces near the ends for receiving the heads and provided with external 20 hoops to bind the whole together, two hoops being usually applied to each end. The staves as they come from the mill must first be provided with the groove on the inner end 25 surfaces thereof and the head must be carefully turned in circular form to fit the exact size of barrel desired. The groove if cut to a considerable depth materially weakens the staves at the ends thereof, or if cut shallow 30 the head is insecurely held in place. The staves and bottom head are assembled in a suitable frame and the upper head thereafter applied thereto. This operation requires a considerable amount of skill and materially 35 adds to the cost of the barrel.

The object of my invention is to do away 40 with the necessity of grooving the ends of the staves and provide a head which can be readily applied to the barrel by unskilled labor and which will also serve as an end hoop, thereby dispensing with those ordinarily used.

It consists, generally stated, in a metallic 45 barrel-head provided with an annular groove on the circumference thereof, which groove is adapted to fit over the end of the staves and provide an inner and outer bearing-surface therefor, and so formed that the head can be easily and securely fastened to the ends of the staves.

50 To enable others skilled in the art to make

and use my invention, I will now describe the same more fully, referring to the accompanying drawings, in which—

Figure 1 is a vertical section of a barrel having my improved heads applied thereto; 55 Fig. 2 is a perspective view, partly in section, of the improved head.

The barrel-body is of the usual and ordinary construction and is made up of the staves 1 and hoops 2 about the middle portion thereof, the end hoops usually found in barrels of this construction being omitted. 60

The improved head comprises a disk 3, of sheet metal, having on its circumference an upwardly-projecting wall 4 and a downwardly-projecting wall 5, substantially parallel to the wall 4, and an annular ring 6, connecting the two walls at the top, thereby providing a groove 7, having substantially-parallel annular walls and opening downward. 70 The walls of the groove are shown slightly inclined from a line perpendicular to the plane of the head in order to conform to the slight inward incline of the ends of the staves; but in heads for use on barrels having substantially-straight staves the walls of the groove will be substantially at right angles to the plane of the head. In some cases it is desirable to strengthen the head, and this may be done by striking up the metal, as 75 shown at 8 9, to form ribs thereon. These ribs are shown at right angles to each other; but it is obvious that they may be placed in any other relation and be of any desired number, and instead of being formed by striking up the metal they may be separate from the head and secured thereto in a variety of ways. The head is preferably made of a single integral piece of sheet metal and is of such form that it can be readily shaped by a 80 single operation of a stamping-machine. It is obvious, however, that it might be made of separate pieces united by soldering or brazing; but the integral form is preferred, it being both stronger and cheaper to manufacture than the built-up form.

In assembling the barrel the lower ends of the staves are inserted in the groove of the lower head, thus dispensing with a portion of the assembling-frame usually employed. The 100

walls of the groove are substantially parallel the entire depth of the groove and are spaced such a distance apart that they bear firmly on the inner and outer sides of the stave-
5 heads, whereby the head is held firmly on the ends of the staves, thus making it possible to move the barrel during the process of assembling without danger of the head falling off. After the hoops 22 have been applied
10 the upper head is slipped over the ends of the staves and the walls of the groove thereof clasp the staves firmly, thus holding the head in place. For barrels filled with light material no other fastening means for the heads
15 is necessary; but if the barrels are to be filled with heavy material the heads are further secured to the barrel-body by means of nails or rivets, as shown at 11. I have shown a hoop 10 at the upper end of the barrel, its function
20 being merely to keep the upper ends of the staves from spreading while the barrel is being filled. The ordinary wooden barrel has

two hoops at each end; but these are dispensed with in my improved barrel, the outer wall 5 on the groove of the head serving as the end 25 hoop.

What I claim as my invention, and desire to secure by Letters Patent, is—

A barrel comprising a body composed of ungrooved wooden staves and hoops, the head 30 comprising a metallic disk provided with a circumferential groove, the walls of which are straight and substantially parallel the entire depth of said groove and bearing tightly on the inner and outer sides of the stave ends, 35 and means extending through the walls of the groove and staves for securing the head to the body.

In testimony whereof I, the said GEORGE F. F. MCKEEVER, have hereunto set my hand. 40
GEORGE F. MCKEEVER.
